SHOE-PRESSING MACHINE

Charles F. Pym, Beverly, Mass., assignor to
 United Shoe Machinery Corporation, Paterson,
 N. J., a corporation of New Jersey

Application September 15, 1930, Serial No. 481,919

84 Claims. (Cl. 12—51)

This invention relates to machines for pressing the bottoms of shoes, and in some important aspects more particularly to machines for pressing the marginal portion of upper materials (hereinafter referred to inclusively as the upper) upon an insole before the outsole is applied to the shoe. In some aspects also the invention has more particular reference to upper-pressing means for use in the manufacture of shoes in which the upper 10 is secured to the insole by an adhesive, and it may be also in which the outsole is thereafter secured adhesively on the shoe bottom, although it is to be understood that the invention is not thus limited in its applicability.

15 For the purposes in view, the invention provides a novel construction and arrangement of means for applying pressure to the marginal portion of an upper extending inwardly over an insole in substantially parallel relation to the shoe 20 bottom, the construction shown comprising heated pressing means shaped in substantial conformity to the desired contour of the portions of the shoe bottom upon which the pressure is applied and so formed as to limit it substantially to engagement with the upper so that the pressure 25 is concentrated upon the margin of the shoe bottom, the illustrated arrangement also being such that the pressing means supports a shoe placed thereon bottom downward. It is a further characteristic of the construction shown that the pressing means comprises members or dies shaped and arranged to apply the pressure along the opposite sides of the shoe bottom. It is to be understood, however, that while the illustrated machine 30 is thus constructed with special reference to treatment of the opposite side portions of the upper, the invention in various novel aspects is not limited in respect to the portion or portions of the shoe bottom where the pressure is applied.

40 It is contemplated that such pressing means may be used with substantial advantages in operating upon shoes the opposite sides of which have been previously lasted, for example by use of a machine of the character disclosed in my copending application, Serial No. 555,035 filed on Aug. 4, 1931, and in which the uppers are held in lasted position by an adhesive which has hardened or set sufficiently to prevent any loss of lasting tension, and yet is more or less yieldable under the 45 application of heavy pressure. By the pressing means described the marginal portion of the upper will be more closely and firmly compacted upon the insole and any irregularities that may remain from the lasting operation will be eliminated, so that the outsole when applied will lie

close to that portion of the upper which is adjacent to the edge of the insole; while the simultaneous application of heat will not only facilitate the elimination of any surface irregularities, but will also under some conditions hasten the drying or setting of the cement or adhesive, so that when the shoe is released from pressure there will be no displacement of the margin of the upper from the position assumed under the pressure. The application of pressure and heat will also further insure that the adhesive will be properly effective in securely uniting the parts. In operating, moreover, on shoes of that type in which the outsole is secured by an adhesive to the margin of the upper on the insole, the heavy pressure applied as described will serve to bring out clearly on the upper the line of the edge of the insole and thus indicate definitely the limit of that portion of the upper which should be roughened before the adhesively coated outsole is placed on the shoe 70 bottom. It is further contemplated that, as an alternative, the shoe may be presented to the machine herein disclosed with the adhesive in a more tacky condition than above described and with temporary fastenings applied to assist in holding the upper in lasted position, in which case the heat of the pressing means will have an especially important function in hastening the setting of the adhesive, so that the fastenings may be thereafter immediately removed, thus effecting an important saving of time in the manufacture of the shoe.

In accordance with a further feature, the invention provides a novel construction and arrangement of means whereby the marginal portion of the upper is subjected to a wiping or ironing action as well as to pressure. As illustrated, the above described pressing members are so mounted and controlled as to move inwardly toward each other as they apply their pressure to the upper. This renders the members more effective in smoothing the upper free from any irregularities in its margin, and the inward wiping action also counteracts any tendency for the upper to bulge at the edge of the shoe bottom under the pressure applied, and may even have a tightening effect on the upper, thus improving the lasted condition of the shoe. For the purpose in view the construction is such that the inward wiping movement 100 of the pressing members occurs in response to pressure of the shoe against them, the members, as illustrated, being controlled by parallel links which are effective against spring resistance to move them inwardly as the pressure is applied 110

without altering their angular relation to the shoe bottom. As the members are moved inwardly over the shoe bottom their pressure on the upper is progressively increased, and after 5 the wiping action the pressure is still further increased. In accordance with another feature there is provided means for preventing outward return movement of the pressing and wiping members until after the shoe has been substantially released from pressure, so as to avoid any possibility of displacement of the margin of the upper by outward drag of the members thereon.

To insure the application of effective pressure on the margin of the upper extending along that 15 portion of the shoe bottom which slopes from the ball of the shoe toward the shank, there is further provided means for effecting relative movement of the shoe and the pressing means in a direction lengthwise of the shoe. In 20 the machine shown the shoe is supported against the pressure applied on its bottom face by a member engaging the top of the heel end of the last and a roll engaging the shoe or last at the top of the forepart; and for the purpose 25 in view the roll is so arranged that it engages the upwardly inclined surface of the shoe or last at the rear of the toe, so that it tends to effect a rearward displacement of the shoe. Insurance is thus afforded that the bottom of the 30 shoe will be pressed firmly against the inclined surfaces of the pressing members immediately at the rear of the ball of the shoe.

The above and other features of the invention, including novel means for positioning the 35 shoe in proper relation to the pressing means, novel means for adjusting the pressing members, and various novel details of construction and combinations of parts, will now be more particularly described by reference to the accompanying drawings and pointed out in the claims.

In the drawings:

Fig. 1 is a view in front elevation of the upper portion of a machine in which the invention is embodied;

Fig. 2 is a similar view on a larger scale of the upper right-hand portion of the structure shown in Fig. 1, with parts broken away;

Fig. 3 is a section on the line III—III of Fig. 2 but showing the parts in the positions that 50 they occupy prior to the application of pressure to the shoe;

Fig. 4 is a section on the line IV—IV of Fig. 2;

Fig. 5 is a section on the line V—V of Fig. 2;

Fig. 6 is a view of the upper right-hand portion of the machine in end elevation;

Fig. 7 is a plan view of the shoe-pressing members and parts associated therewith;

Fig. 8 is a vertical section lengthwise of a shoe in position for the pressing operation, with 60 one of the pressing members shown in elevation;

Fig. 9 is a cross-sectional view showing the upper-pressing members in their initial relation to a shoe in which tacks are used to assist temporarily in holding the upper in lasted position;

Fig. 10 is a view similar to Fig. 9, illustrating the positions of the parts with the shoe under pressure; and

Fig. 11 is a perspective view illustrating the condition of the bottom of a shoe after it has been operated upon by the machine.

The invention is herein illustrated as applied to a machine organization of the same general type as disclosed in Letters Patent No. 1,549,243, granted on August 11, 1925, upon an application 75 of E. E. Winkley. Only such parts of the ma-

chine, therefore, as it is necessary particularly to refer to for an understanding of the invention are herein shown and will be described in detail.

A machine of the type illustrated is a twin machine, comprising two sets of instrumentalities which are substantial duplicates of each other and are operated alternately to apply pressure to different shoes, the arrangement being such that as a shoe is subjected to pressure by either set of instrumentalities a shoe previously operated upon by the other set is released from pressure. Associated with each set of instrumentalities are a pair of vertical rods 20 which support adjustably near their upper ends a cross-head 22. Adjustable on guideways 24 on the opposite sides of each cross-head 22 are a toe post 26 and a heel post 28 which serve to support the shoe against upwardly directed pressure applied on its bottom face, the toe post having a rubber covered roll 30 thereon for engaging the shoe or last on the top of the forepart and the heel post in the construction shown having a plate 32 arranged to engage the top face of the heel-end portion of the last. The plate 32 is mounted on a block 34 which is pivoted at 36 on the heel post and is provided with a screw 38 for engaging the heel post to limit adjustably the movement of the block in one direction. A leaf spring 40 which is fast on the heel post and bears on the block 34 maintains the block normally in the position determined by the screw. 100 It will be understood that by means of the screw 38 the plate 32 may be adjusted so that it will bear evenly upon the top of the last. The toe post 26 and the heel post 28 are connected together and to a hand wheel 42 by which they 110 may be moved simultaneously toward or from each other, as heretofore in machines of the type illustrated. Threaded in the toe post 26 is a screw 44 which is arranged to bear on one of the guideways 24 to assist in holding the parts in adjusted 115 positions.

Included in each set of instrumentalities is a slide 46 vertically movable on the rods 20 which serve as guides therefor, each slide being operated by a toggle, one of the arms of which is shown 120 at 48. As shown and described in detail in the above-mentioned Letters Patent, the different toggles are connected together for movements in such relation to each other that when one is straightened to apply pressure to a shoe the other 125 is broken to release a shoe to which pressure was previously applied, a heavy spring 50 being associated with the different toggles to apply the pressure, first through one of them and then through the other. Each slide 46 supports a box 52 provided with a pair of trunnions 54 mounted in bearings on the slide, so that the box may tip about an axis extending laterally of the shoe. The box is maintained normally in a predetermined position by means of a spring-controlled 130 plunger 58 which is carried by the box and bears against the slide 46, combined with a spring 60 which acts on the box to hold the plunger 58 against the slide. It will be understood that by this means the box 52 is steadied and maintained 135 normally in a predetermined position, but is permitted to tip about the axis of the trunnions 54 in one direction or the other as the pressure is applied to the shoe. As thus far described the machine herein shown is constructed substantially as disclosed in the above-mentioned Letters Patent, except for the provision of the last-engaging plate 32 in place of the heel pin shown in the patent.

Vertically movable in each box 52 is a casting 150

62 supported by four springs 64 which are yieldable in response to resistance of the shoe to the pressure applied. Mounted in guideways on the casting 62 for movement in directions widthwise of the shoe is a slide 66 which is adjustable along the guideways by means of a screw 68 held against lengthwise movement by a lug 70 fast on the casting. Mounted in guideways on the slide 66 for movements in directions lengthwise of the shoe is a slide 72 which is adjustable along the guideways by means of a screw 74 held against lengthwise movement relative to the slide 72 by a plate 76 that is fast on the slide 72, the screw being threaded in a lug 78 on the slide 66 and having a hand wheel 79 thereon for turning it. The slide 72 serves as a support for four brackets 80 controlled as hereinafter described, two of these brackets being located opposite each other near the toe end of the shoe and the other two opposite each other near the heel end of the shoe. Connected by parallel links 82 and 84 to each of the brackets 80 is an angularly shaped holder 86, and each pair of similarly arranged holders 86 serves to support a metal block 88 on which is mounted one of a pair of inflexible shoe-pressing members or dies 90, 92. The blocks 88 are positioned and secured on the holders 86 by dowel pins 94 which project upwardly into recesses formed in the blocks and by spring-controlled plungers 96 which are movably mounted in the holders 86 and project into recesses formed in the sides of the blocks. The spring plungers 96 are controlled by handles 98 by which they may be withdrawn from the recesses in order to release the blocks and permit them to be lifted from the holders 86. Each of the pressing members 90, 92 has a tongue-and-groove connection 100 with its supporting block 88 to maintain it in the proper lateral position, as illustrated in Figs. 3 and 4, and is held in proper lengthwise position by means of a dowel pin 102 (Fig. 4) which projects from the block into a recess in the pressing member. It will be evident that the pressing members are so mounted as to permit them to be readily removed simply by lifting them from the blocks 88, so that different members may be conveniently substituted for use on shoes of different styles or sizes.

One of the pair of parallel links supporting each holder 86 on the bracket 80, namely the link 82, has an extension 104 provided with a slot through which projects a rod 106 pivoted at its lower end on the bracket 80, and encircling this rod is a spring 108 which bears at its lower end on a washer 110 that rests against the extension 104 and at its upper end on a wing nut 112. It will thus be seen that the springs 108 by their action on the links 82 tend to maintain the holders 86 in upraised positions, as illustrated in Fig. 3, in which their outer side faces are against the upwardly extending portions of the brackets 80. The shoe-pressing members 90, 92 are accordingly presented initially in upraised positions at considerable distances from each other, and as thus presented they are adapted to receive and support a shoe placed thereon bottom downward. When the pressure is applied to the shoe by upward movement of the slide 46, the resistance of the shoe to the upward movement of the pressing members 90, 92, after upward movement of the shoe has been stopped by the members 30 and 32, causes the parallel links 82, 84 to be swung from their initial positions into positions such as indicated in Fig. 4, whereby the shoe-pressing members are forced bodily inward toward each other

with a wiping action on the margin of the upper. It will be understood that such movement occurs against the increasing resistance of the springs 108 through which the pressing members are pressed against the shoe during the wiping action. The swinging of the parallel links is limited by engagement of the lower faces of the holders 86 with the brackets 80, after which increased pressure is applied to the shoe through the springs 64 without any wiping action, the pressure being substantially uniform all along the sides of the shoe bottom. It will be understood that by adjustment of the nuts 112 the initial compression of the different springs 108 may be varied, so as to vary the amount of pressure applied to the shoe by the pressing members during their wiping action on the upper.

The shoe-engaging portions of the pressing members or dies 90, 92 are shaped in substantial conformity to the desired contour of the portions of the bottom of the shoe which they engage and are accordingly curved more or less lengthwise of the shoe to fit the curved portions of the shoe bottom, and they are also so shaped and arranged as to limit them substantially to engagement with the marginal portion of the upper extending inwardly over the insole, so that their pressure is substantially confined to the upper. It is contemplated that before the shoe is presented to the illustrated machine its toe and heel end portions will have been previously lasted in such manner that the margin of the upper in those locations will require no further pressing treatment. The pressing members, however, in the construction shown, are so formed as to extend throughout the length of the shoe, and therefore overlap portions of the margin of the upper at the sides of the toe and heel ends. Accordingly supplemental pressure also is applied in these locations, and uniformity in the condition of the margin of the upper throughout the length of the shoe bottom is insured. By reference to Fig. 7 it will be seen that the inner edges of the shoe-engaging portions of the pressing members are shaped in approximate conformity to the edge contour of the shoe bottom, to assist in limiting the members only to engagement with the marginal portion of the upper. Accordingly, the members that operate on the opposite sides of the shoe bottom are shaped differently from each other, and the pair of members that operate on a right shoe are shaped differently from the pair that operate on a left shoe. In the machine illustrated the pairs of pressing members suitable for right and left shoes, respectively, will preferably be used in the opposite halves of the machine. It is contemplated that the same pair of pressing members may be used in operating on shoes of a number of different sizes, although for wide variations in size, as well as for variations in style, differently formed pressing members will be substituted.

The machine is further provided with means whereby the pressing members 90, 92 and their supports may be suitably adjusted in accordance with the width of the shoe. To this end, the four brackets 80 previously referred to as mounted on the slide 72 are connected to corresponding blocks 114 which are movable in directions widthwise of the shoe in recesses in the slide 72. As illustrated in Fig. 3, the connections between the blocks 114 and the two brackets 80 that are located nearest the toe end of the shoe comprise headed studs 116 which are fast on the brackets and are swiveled in the blocks, and as illustrated in Fig. 5 the blocks located near the heel end of

the shoe have projections that are swiveled in openings in the brackets, the connections further including screws 118 which are threaded in the blocks and overlap portions of the brackets.

5 Accordingly, each of the brackets 80, while movable widthwise of the shoe with its connected block 114, may turn relatively to the block about a vertical axis. The two blocks 114 that are nearest the toe end of the shoe (Fig. 3) are adjusted toward or from each other by means of a shaft 120 which is mounted in bearings in the slide 72 and has right and left threads thereon engaging the respective blocks, the shaft being held from lengthwise movement by collars 122

10 which are fast thereon within a recess in the slide 72. Fast on the shaft 120 is a hand wheel 124 for turning it. The two blocks 114 that are nearest the heel end of the shoe (Fig. 5) are adjusted toward or from each other by a shaft 126

15 which has right and left threads engaging the respective blocks and is mounted in bearings in the slide 72 and held from lengthwise movement in substantially the same manner as the shaft 120. The two shafts 120 and 126 are connected

20 together by a rack bar 128 supported on the slide 72 and engaging a pinion 130 on the shaft 120 and a pinion 132 on the shaft 126, so that both shafts are turned simultaneously by the hand wheel 124. Since variations in width are more

25 pronounced at the forepart than at the heel end, the threads on the shaft 120 are of steeper pitch than the threads on the shaft 126, so that greater movements toward or from each other are imparted to the portions of the shoe-pressing members that are nearest the toe end of the shoe than to the portions near the heel end by the same movement of the hand wheel 124. As illustrated, the hub of the hand wheel 124 is provided with a flange 134 which has size indications

30 thereon arranged to cooperate with width indications marked on the adjacent surface of the slide 72 as a guide in adjusting the pressing members.

The machine is further provided with means for maintaining the shoe-pressing members 90, 92 in a heated condition. For this purpose there is mounted in a recess in each end of each block 88 an electrical heating unit 136, and from the four units in each set of instrumentalities electrical conductors 138 lead to an outlet box 140 fast on the vertically movable slide 46. From each outlet box 140 electrical conductors mounted within a flexible cable 142 lead to a switch box 144 on the frame of the machine. From the blocks 88 the heat is conducted to the shoe-pressing members mounted thereon.

In order to avoid any possibility of displacement of the marginal portion of the upper from its proper relation to the insole in the return of the parts of the upper-pressing means to their starting positions, there is provided means for preventing the pressing members 90, 92 from moving outwardly away from each other until after the shoe has been substantially released from pressure. This means comprises a latch 146 mounted adjacent to each pair of opposite holders 86 and arranged to engage projections 148 on the two holders when the parts are in the positions that they assume at the end of the pressure-applying operation and thus to prevent the holders from being returned to their starting positions by the parallel links 82, 84 and the springs 108 until after the slide 46 and the parts supported thereon have been moved downwardly far enough to release the shoe from pres-

sure. Each latch 146 is fast on a rock shaft 150 (Fig. 6) supported in bearings on an end of the slide 72 and is connected to a spring 152 which tends to swing it into operative relation to the projections 148. Fast on the end of each rock shaft 150 is an arm 154 pivotally connected to the outer end of which is a rod 156 extending upward loosely through an opening in a block 158 fast on one of the rods 20. A nut 160 on the upper end of each rod 156 is arranged to cooperate with the block 158 to hold the latch 146 in an idle position when the slide 46 and the parts supported thereon are in their lowest positions. When the slide 46 is moved upwardly to apply pressure to a shoe the two nuts 160 are released from control of the block 158, thus permitting the springs 152 to swing the latches 146 into positions to catch on the projections 148 as soon as the holders 86 are lowered far enough relatively to the brackets 80 to carry these projections below the latches. In the return of the parts to starting positions the nuts 160 do not arrive in positions to engage the block 158 until the slide 46 has been lowered far enough to carry the shoe away from the shoe support members 30 and 32, so that the latches remain in positions such as to prevent the upward and outward swinging movements of the holders 86 until after the shoe has been released from pressure. Thereafter the block 158 acts on the nuts 160 to cause the latches 146 to swing outwardly and release the holders, whereupon the latter are returned to their starting positions by the springs 108. At this time the shoe merely rests by its own weight on the pressing members 90, 92 and accordingly the pressure of these members on the shoe is not great enough to involve any danger of displacement of the upper by the outward movements of the members.

When the operator places the shoe on the pressing members 90, 92, the contour of these members, conforming substantially to the lengthwise curvature of the shoe bottom, affords a sufficiently definite indication of the proper lengthwise position of the shoe. To determine the proper lateral position of the shoe, the machine is provided with gages located at the opposite sides of the forepart of the shoe and with other gages located at the opposite sides of its heel end. Each of the forepart gages comprises a metal plate 162 bent into the shape illustrated in Figs. 3 and 4 and pivoted on studs 164 on a supporting block 166 so that the plate is free to turn about a vertical axis to adjust itself to the contour of the shoe. Fast on the plate 162 is a piece of soft material 168 such as leather or rubber arranged to contact with the shoe. The block 166 is swiveled on the end of a screw 170 which is threaded in an upright supporting arm 172, and a part of the plate 162 overlaps a plate on the upper end of the arm to prevent the plate 162 from turning about a horizontal axis. The two arms 172 are mounted in a guideway extending laterally of the shoe in a plate 174 which is secured on the slide 72 and are adjustable toward or from each other by a shaft 176 having right and left threads engaging the respective arms and provided with a knurled head 178 for turning it. The shaft 176 is held from lengthwise movement by collars 180 which are fast thereon at the opposite sides of a plate 182 secured on the supporting plate 174. It will thus be seen that the two gages are adjustable simultaneously toward or from each other by the shaft 176 and are also adjustable each independently of the

other by the screws 170 for properly positioning shoes of different sizes and styles.

The back seam of each shoe should be centralized laterally with respect to the two pressing members 90, 92, and for this purpose there are provided gages 184 (Figs. 2 and 7) consisting of arms mounted on a block 186 for swinging movements toward or from each other at the opposite sides of the heel end of the shoe and connected by gear teeth 188 to swing in unison, each arm having a leather cover 190 thereon to contact with the shoe. The two arms 184 are adjusted toward or from each other by a shaft 192 having right and left threads in engagement with blocks 194 that are swiveled on the outer ends of the respective arms, the shaft having a knurled head 196 thereon for turning it. The supporting block 186 is pivoted at 198 on a standard 200 which is mounted on the casting 62, so that the arms 184 may be swung out of operative position to facilitate removal of the pressing members 90, 92. A spring 202 connected to one of the arms 184 and to the standard 200 holds the arms normally in operative position, the arrangement of this spring in relation to the axis 198 being such that it will also maintain the arms in inoperative position when they are swung to that position.

In order to insure the application of adequate pressure on the upwardly sloping portion of the shoe bottom immediately at the rear of the ball of the shoe by the complementally shaped portions of the pressing members 90, 92, it is contemplated that the roll 30, as illustrated, will be so adjusted as to engage the shoe or last on its upwardly inclined top face at the rear of the toe and thus effect somewhat of a rearward displacement of the shoe as the pressure is applied, so as to force it hard against the above-mentioned portions of the pressing members. It will be evident that the plate 32 engaging the top of the heel end of the last does not prevent such rearward movement of the shoe.

In the operation of the machine, after pressing members 90, 92 suitable for the style and size of shoe to be operated upon have been mounted on the supporting blocks 88 of each half of the machine and have been heated to the desired temperature, and after proper adjustments of various parts including the holders 86 and the gages 162 and 184 have been made, the operator places a shoe bottom downward upon that pair of pressing members which is in its lowest position. While the invention is not limited to the particular use illustrated, the shoes herein shown are of that type in which the marginal portion of the upper is lasted inwardly over an insole in generally parallel relation to the shoe bottom and secured in lasted position along the forepart and shank portions of the shoe bottom by an adhesive, and in which an outsole is thereafter cemented to the lasted margin of the upper. Before the shoe is presented to this machine, in accordance with the illustrated practice, it will have been previously lasted at its toe and heel ends and also at its opposite sides between its toe and heel end portions. The heel end portion of the upper may be fastened in lasted position by tacks, as shown, and the toe end portion by cement; and it is further contemplated that the lasting of the toe and heel ends will have been performed in such manner that the upper in these locations will not require any further pressing prior to the attachment of the outsole, although the machine here-

in shown is so constructed as to apply some pressure at the sides of the toe and heel ends, as hereinbefore explained. Along the opposite sides between the toe and heel end portions the upper will be held in lasted position either by an adhesive alone or by an adhesive supplemented by a few temporary lasting tacks. In either case the adhesive or cement will not be completely hardened or set, but will still be in such condition as to yield more or less under the application of pressure. If the shoe is one in which tacks are used, they will assume positions between the two pressing members 90, 92, as illustrated in Fig. 9.

After placing a shoe in position to be operated upon, as above described, the operator starts the power operation of the machine, whereupon the slide 46 at that side of the machine where the shoe was placed is elevated and the slide at the other side is lowered. The shoe is accordingly raised until stopped by the abutment members 30 and 32, and when this occurs the pressure of the bottom of the shoe against the members 90, 92 causes the links 82, 84 to swing from their initial inclined positions (Fig. 3) to positions more nearly horizontal (Fig. 4) as the supporting brackets 80 continue their upward movement, so that the pressing members are forced inwardly over the shoe bottom in wiping engagement with the marginal portion of the upper. Such inward movement of the pressing members occurs only after the pressure of the shoe thereon is great enough to overcome the resistance of the springs 108, which are further compressed during the wiping action and therefore subject the upper to increasing pressure at that time. In this manner the marginal portion of the upper is firmly compacted upon the insole while being subjected to a wiping action which not only prevents it from being squeezed outwardly at the edge of the insole by the pressure applied, but may even draw it more tightly inward over the insole; and at the same time any surface irregularities in the margin of the upper are ironed out by the heated pressing members. If the shoe is one in which lasting tacks are used, they may be crowded or bent inwardly more or less, as illustrated in Fig. 10. The inward wiping action of the pressing members is terminated by engagement of the holders 86 with the brackets 80, and thereafter the upper is subjected to further pressure through the springs 64 and the heavy toggle-controlling spring 50. In the course of the upper-pressing operation the roll 30 acts on the sloping top face of the shoe or last to effect more or less of a rearward displacement of the shoe such as to insure effective pressure upon the margin of the upper along that portion of the shoe bottom which slopes rearwardly from the ball of the shoe.

The machine comes automatically to a stop with the shoe under pressure, and while the shoe is held under pressure the operator presents a shoe to the other half of the machine. The machine will be permitted to remain at rest long enough to render the heat properly effective on the cement, so that when the shoe is released from pressure the cement will have set firmly enough to maintain the upper securely in its pressed condition. The length of time required will depend upon the character and condition of the cement. When the machine is again started, the shoe to which pressure was applied is released and the shoe presented to the other half of the machine is subjected to pressure. As the slide 46 is lowered to release the shoe, the latches 146

80

prevent upward and outward swinging movements of the holders 86 under the influence of the springs 108 until after the shoe has been carried downwardly away from the abutment members 30 and 32 and thus released from pressure. Near the end of the downward movement of the slide the latches are operated to release the holders, thus rendering the springs 108 effective to return the pressing members 90, 92 to their starting positions. Since the shoe rests merely by its own weight on these members at that time, there is no danger of any displacement of the margin of the upper by the outward movement of the members.

15 Fig. 11 shows the bottom of a shoe as it appears after it has been operated upon by the machine, any lasting tacks that may have been used having been removed. In addition to other desirable effects hereinbefore discussed, the pressing and wiping action of the machine on the marginal portion of the upper serves to bring out clearly on the upper the outline of the edge of the insole, as illustrated at *a*, so that a definite indication is afforded of the limit of that portion of the upper that should be roughened preparatory to the laying of a cement-coated outsole thereon.

Having described the invention, what I claim as new and desire to secure by Letters Patent of the United States is:

30 1. In a machine for pressing the bottoms of shoes, pressing means constructed and arranged to engage initially and press the marginal portion of an upper previously laid inwardly over an insole substantially in lasted position, said pressing means having an inflexible shoe-engaging portion curved lengthwise of the edge of the insole in substantial conformity to the desired contour of the shoe bottom and so constructed as to limit it substantially to operation on said marginal portion of the upper.

40 2. In a machine for pressing the bottoms of shoes, pressing means constructed and arranged to engage initially and press the marginal portion of an upper previously laid inwardly over an insole in substantially parallel relation to the shoe bottom, said pressing means being curved lengthwise of the edge of the insole in substantial conformity to the desired contour of the shoe bottom and so constructed as to limit it substantially to engagement with said marginal portion of the upper, and means for heating said pressing means.

45 3. In a machine for pressing the bottoms of shoes, pressing means constructed and arranged to engage initially and press the marginal portion of an upper previously laid inwardly over an insole substantially in lasted position along the opposite sides of the bottom of a shoe between its toe and heel end portions, said pressing means being curved lengthwise of the shoe in substantial conformity to the desired contour of the shoe bottom and so constructed as to limit it substantially to operation on said marginal portion of the upper, and mechanism for effecting relative movement of the shoe and said pressing means heightwise of the shoe to apply substantially uniform pressure along the opposite sides of the shoe bottom.

50 4. In a machine for pressing the bottoms of shoes, pressing means arranged to support a shoe placed initially thereon bottom downward and constructed to press the marginal portion of the shoe upper extending inwardly over an insole, said pressing means being shaped in substantial conformity to the desired contour of the shoe bottom lengthwise of the edge of the insole and so constructed

bottom and so constructed as to limit it substantially to operation on the upper.

55 5. In a machine for pressing the bottoms of shoes, pressing means arranged to support a shoe placed initially thereon bottom downward and constructed to engage and press the marginal portion of the shoe upper extending inwardly over an insole substantially in lasted position, said pressing means being shaped in substantial conformity to the desired contour of the shoe bottom lengthwise of the edge of the insole and so constructed as to limit it substantially to engagement with said marginal portion of the upper, and means for heating said pressing means.

60 6. In a machine for pressing the bottoms of shoes, pressing means arranged to support a shoe placed thereon bottom downward and constructed to press the marginal portion of the shoe upper extending inwardly over an insole along the opposite sides of the bottom of the shoe between its toe and heel end portions, said pressing means being shaped in substantial conformity to the desired contour of the shoe bottom lengthwise of the shoe and so constructed as to limit it substantially to operation on said marginal portion of the upper.

65 7. In a machine for pressing the bottoms of shoes, pressing means arranged to support a shoe placed initially thereon bottom downward and constructed to engage and press the marginal portion of the shoe upper extending inwardly over an insole along the opposite sides of the forepart and shank portions of the bottom of the shoe, said pressing means having its shoe-engaging portion curved in substantial conformity to the desired contour of the shoe bottom along the forepart and shank and so constructed as to limit it substantially to engagement with the upper, and means for heating said pressing means.

70 8. In a machine for pressing the bottoms of shoes, pressing members constructed and arranged to support a shoe placed thereon bottom downward and to press the marginal portion of the shoe upper extending inwardly over an insole in substantially parallel relation to the shoe bottom along the opposite sides of the shoe between its toe and heel end portions, said members being arranged to extend only part way inwardly over the shoe bottom to limit them substantially to operation on the upper, and means for heating said members.

75 9. In a machine for pressing the bottoms of shoes, pressing members constructed and arranged to support a shoe placed initially thereon bottom downward and to engage and press the marginal portion of the shoe upper extending inwardly over an insole substantially in lasted position along the opposite sides of the forepart and shank portions of the bottom of the shoe, said members being curved in substantial conformity to the desired contour of the shoe bottom and arranged to extend only part way inwardly over the shoe bottom to limit them substantially to engagement with the upper, and means for heating said members.

80 10. In a machine for pressing the bottoms of shoes, pressing means constructed and arranged to engage initially and press the marginal portion of an upper previously laid inwardly over an insole substantially in lasted position, said pressing means being curved in substantial conformity to the desired contour of the shoe bottom lengthwise of the edge of the insole and so constructed

as to limit it substantially to engagement with said marginal portion of the upper, and mechanism for effecting relative movement of the shoe and said pressing means to cause said means to wipe the upper.

11. In a machine for pressing the bottoms of shoes, pressing means constructed and arranged to engage initially and press the marginal portion of an upper extending inwardly over an insole in substantially parallel relation to the shoe bottom, said pressing means being shaped in substantial conformity to the desired contour of the shoe bottom lengthwise of the edge of the insole and so constructed as to limit it substantially to engagement with said marginal portion of the upper, means for heating said pressing means, and means for effecting relative movement of the shoe to apply the pressure and for also moving said pressing means inwardly over the shoe bottom in wiping engagement with the upper.

12. In a machine for pressing the bottoms of shoes, pressing members constructed and arranged to engage initially and press the marginal portion of an upper previously laid inwardly over an insole substantially in lasted position along the opposite sides of the bottom of a shoe at the rear of the toe portion, said pressing members being mounted for bodily movements toward each other to wipe the upper over the insole.

13. In a machine for pressing the bottoms of shoes, pressing members constructed and arranged to engage initially and press the marginal portion of an upper previously laid inwardly over an insole along the opposite sides of the bottom of a shoe between its toe and heel end portions, said members being curved lengthwise of the shoe in substantial conformity to the desired contour of the shoe bottom, means for heating said members, and means for operating them to wipe the upper inwardly over the insole.

14. In a machine for pressing the bottoms of shoes, pressing members constructed and arranged to act on a previously lasted shoe to engage initially and press the marginal portion of the upper previously laid inwardly over an insole along the opposite sides of the forepart and shank portions of the bottom of the shoe, means for heating said members, and means for operating them to wipe the previously lasted upper in directions inwardly over the insole.

15. In a machine for pressing the bottoms of shoes after lasting, heated pressing means constructed and arranged to engage initially the previously lasted marginal portion of an upper extending inwardly over an insole in generally parallel relation to the shoe bottom and adhesively connected to the insole, said pressing means being movable inwardly over the shoe bottom in wiping engagement with the previously lasted upper to tighten the upper and smooth its margin free from wrinkles while applying heat to hasten the setting of the adhesive.

16. In a machine for pressing the bottoms of shoes after lasting, heated pressing members constructed and arranged to engage initially the previously lasted marginal portion of an upper extending inwardly over an insole in generally parallel relation to the shoe bottom at its opposite sides between its toe and heel end portions and adhesively connected to the insole, said members being movable inwardly over the shoe bottom in wiping engagement with the previously lasted upper to tighten the upper and smooth its margin

free from wrinkles while applying heat to hasten the setting of the adhesive.

17. In a machine for pressing the bottoms of shoes after lasting, pressing means constructed and arranged to engage initially the marginal portion of an upper held substantially in lasted position over the bottom face of an insole, and automatic mechanism for moving said pressing means inwardly over the shoe bottom in wiping engagement with the upper while applying progressively increasing pressure to the upper heightwise of the shoe.

18. In a machine for pressing the bottoms of shoes after lasting, pressing means constructed and arranged to engage initially the marginal portion of an upper held substantially in lasted position over the bottom face of an insole, and automatic mechanism for moving said pressing means inwardly over the shoe bottom in wiping engagement with the upper and for thereafter applying increased pressure to the upper heightwise of the shoe through said pressing means.

19. In a machine for pressing the bottoms of shoes after lasting, heated pressing means constructed and arranged to engage initially the marginal portion of an upper extending inwardly over an insole substantially in lasted position, and mechanism for operating said pressing means with an inward wiping action on the upper while applying progressively increasing pressure to the upper heightwise of the shoe and for thereafter further increasing said pressure without any wiping action on the upper.

20. In a machine for pressing the bottoms of shoes after lasting, heated pressing members constructed and arranged to engage the marginal portion of an upper extending inwardly over an insole substantially in lasted position at the opposite sides of the bottom of a shoe between its toe and heel end portions, and automatic means for moving said members inwardly over the shoe bottom in wiping engagement with the upper while applying progressively increasing pressure to the upper heightwise of the shoe.

21. In a machine for pressing the bottoms of shoes after lasting, pressing members constructed and arranged to engage initially the marginal portion of an upper extending inwardly over an insole substantially in lasted position at the opposite sides of the bottom of a shoe between its toe and heel end portions, and automatic means for moving said members inwardly over the shoe bottom in wiping engagement with the upper and for thereafter applying increased pressure to the upper heightwise of the shoe through said members.

22. In a machine for pressing the bottoms of shoes after lasting, heated pressing members constructed and arranged to engage the marginal portion of an upper extending inwardly over an insole substantially in lasted position along the opposite sides of the forepart and shank portions of the bottom of a shoe, and means for moving said members inwardly over the shoe bottom in wiping engagement with the upper while applying progressively increasing pressure to the upper heightwise of the shoe and for thereafter further increasing said pressure without any wiping action on the upper.

23. In a machine for pressing the bottoms of shoes after lasting, heated pressing means constructed and arranged to engage the lasted marginal portion of an upper extending inwardly over an insole in generally parallel relation to the shoe bottom and adhesively connected to the insole,

- and mechanism for moving said pressing means inwardly over the shoe bottom in wiping engagement with the upper to tighten the upper and smooth its margin free from wrinkles and for thereafter increasing the pressure on the upper heightwise of the shoe while applying heat to hasten the setting of the adhesive. 5
24. In a machine for pressing the bottoms of shoes after lasting, heated pressing means constructed and arranged to engage the lasted marginal portion of an upper extending inwardly over an insole in generally parallel relation to the shoe bottom and adhesively connected to the insole, and automatic mechanism for moving said 10 pressing means inwardly over the shoe bottom in wiping engagement with the upper under progressively increasing pressure to tighten the upper and smooth its margin free from wrinkles and for thereafter further increasing the pressure on the upper heightwise of the shoe while applying heat to hasten the setting of the adhesive. 15
25. In a machine for pressing the bottoms of shoes, pressing means arranged to support a shoe placed thereon bottom downward and constructed to engage and press the marginal portion of the shoe upper extending inwardly over an insole, said pressing means being movable to wipe the upper over the insole while applying pressure thereto. 20
26. In a machine for pressing the bottoms of shoes, pressing means arranged to support a shoe placed initially thereon bottom downward and constructed to engage and press the marginal portion of the shoe upper extending inwardly over an insole, means for heating said pressing means, and mechanism for moving said pressing means to wipe the upper inwardly over the insole while applying pressure thereto. 25
27. In a machine for pressing the bottoms of shoes, pressing means arranged to support a shoe placed initially thereon bottom downward and constructed to engage and press the marginal portion of the shoe upper extending inwardly over an insole, said pressing means being curved lengthwise of the edge of the insole in substantial conformity to the desired contour of the shoe bottom and so constructed as to limit it substantially to engagement with the upper, means for heating said pressing means, and mechanism for moving said pressing means to wipe the upper inwardly over the insole while applying pressure thereto. 30
28. In a machine for pressing the bottoms of shoes, pressing means arranged to support a shoe placed thereon bottom downward and constructed to engage and press the marginal portion of the shoe upper extending inwardly over an insole at the opposite sides of the bottom of the shoe between its toe and heel end portions, said pressing means being curved lengthwise of the shoe in substantial conformity to the desired contour of the shoe bottom, and mechanism for moving said pressing means inwardly over the shoe bottom in wiping engagement with the upper. 35
29. In a machine for pressing the bottoms of shoes, pressing members arranged to support a shoe placed thereon bottom downward and constructed to engage and press the marginal portion of the shoe upper extending inwardly over an insole along the opposite sides of the forepart and shank portions of the shoe bottom, said members being curved in substantial conformity to the desired contour of the shoe bottom, means for 40 heating said members, and means for moving them inwardly over the shoe bottom in wiping engagement with the upper. 45
30. In a machine for pressing the bottoms of shoes, means for applying pressure to the bottom of a shoe before an outsole is applied to the shoe, and mechanism for effecting relative movement of the shoe and said pressure-applying means to cause said means to wipe the bottom of the shoe in response to pressure of the shoe thereon. 50
31. In a machine for pressing the bottoms of shoes, means for applying pressure to the bottom of a shoe before an outsole is applied to the shoe, and parallel links arranged to control said pressure-applying means and to move it over the bottom of the shoe in response to pressure of the shoe on said means. 55
32. In a machine for pressing the bottoms of shoes, means for applying pressure to the marginal portion of an upper on the bottom of a shoe, and mechanism for moving said pressure-applying means inwardly over the shoe bottom in wiping engagement with the upper in response to pressure of the shoe on said means. 60
33. In a machine of the class described, a wiper for wiping the marginal portion of an upper inwardly over the bottom of a shoe, said wiper being movable inwardly over the shoe bottom in response to pressure of the shoe against it. 65
34. In a machine of the class described, a wiper for wiping the marginal portion of an upper inwardly over the bottom of a shoe, and parallel links arranged to move said wiper inwardly over the shoe bottom in response to pressure of the shoe against it. 70
35. In a machine for pressing the bottoms of shoes, means for applying pressure to the bottom of a shoe before an outsole is applied to the shoe, a support for said pressure-applying means, said support and the shoe being relatively movable heightwise of the shoe to cause said means to press on the shoe bottom, and mechanism for moving said pressure-applying means inwardly over the shoe bottom in response to such relative movement. 75
36. In a machine for pressing the bottoms of shoes, means for applying pressure to the bottom of a shoe before an outsole is applied to the shoe, a support for said pressure-applying means, said support and the shoe being relatively movable heightwise of the shoe to cause said means to press on the shoe bottom, and parallel links connecting said pressure-applying means and its support and movable to force said means inwardly over the shoe bottom in response to the relative movement of the shoe and said support. 80
37. In a machine for pressing the bottoms of shoes, means for applying pressure to the bottom of a shoe before an outsole is applied to the shoe, a member movable heightwise of the shoe to cause said means to press on the shoe bottom, and mechanism for forcing said pressure-applying means inwardly over the shoe bottom in response to the movements of said member heightwise of the shoe. 85
38. In a machine for pressing the bottoms of shoes, means for applying pressure to the bottom of a shoe before an outsole is applied to the shoe, a member movable heightwise of the shoe to cause said means to press on the shoe bottom, and a parallel link connection between said member and the pressure-applying means for forcing said means inwardly over the shoe bottom in response to pressure of the shoe against said means. 90

39. In a machine for pressing the bottoms of shoes, pressing means arranged to support a shoe placed thereon bottom downward, and mechanism for moving said pressing means inwardly over the 5 shoe bottom in response to pressure of the shoe thereon. 80
40. In a machine for pressing the bottoms of shoes, pressing means arranged to support a shoe placed thereon bottom downward and constructed to engage and press the marginal portion of the shoe upper extending inwardly over an insole, and mechanism for moving said pressing means inwardly over the shoe bottom in wiping engagement with the upper in response to pressure of the shoe on said means. 85
41. In a machine for pressing the bottoms of shoes, pressing members arranged to press the marginal portion of an upper extending inwardly over an insole along the opposite sides of the 20 bottom of a shoe between its toe and heel end portions, and means for moving said members inwardly over the shoe bottom in response to pressure of the shoe against them. 90
42. In a machine for pressing the bottoms of 25 shoes, pressing members arranged to press the marginal portion of an upper extending inwardly over an insole along the opposite sides of the bottom of a shoe between its toe and heel end portions, and parallel links arranged to control 30 said members and to move them inwardly over the shoe bottom in response to pressure of the shoe against them. 100
43. In a machine of the class described, wipers for wiping the marginal portion of an upper inwardly at the opposite sides of the bottom of a 35 shoe, and mechanism for moving said wipers inwardly over the shoe bottom in response to pressure of the shoe against them. 105
44. In a machine for pressing the bottoms of 40 shoes, pressing members arranged to press the marginal portion of an upper extending inwardly over an insole along the opposite sides of the forepart and shank portions of the bottom of a shoe, said members being curved in substantial 45 conformity to the desired contour of the shoe bottom, means for heating said members, and mechanism for moving said members inwardly over the shoe bottom in wiping engagement with the upper in response to pressure of the shoe against them. 115
45. In a machine for pressing the bottoms of 50 shoes, pressing members arranged to support a shoe placed thereon bottom downward and to engage and press the marginal portion of the shoe upper extending inwardly over an insole along 55 the opposite sides of the bottom of the shoe, and means for moving said members inwardly over the shoe bottom in response to pressure of the shoe against them. 125
46. In a machine for pressing the bottoms of 60 shoes, pressing members arranged to support a shoe placed thereon bottom downward and to engage and press the marginal portion of the shoe upper extending inwardly over an insole along the opposite sides of the forepart and shank 65 portions of the bottom of the shoe, and parallel links arranged to control said members and to move them inwardly over the shoe bottom in wiping engagement with the upper in response to pressure of the shoe against them. 135
47. In a machine for pressing the bottoms of 70 shoes, pressing means movable inwardly over the bottom of a shoe laterally of the shoe in response to pressure of the shoe thereon, and spring means for yieldingly opposing the inward movement of 75 said pressing means. 140
48. In a machine for pressing the bottoms of shoes, means for applying pressure to the bottom of a shoe, mechanism for moving said pressure-applying means inwardly over the bottom of the shoe laterally of the shoe in response to pressure of the shoe against said means, and spring means arranged yieldingly to oppose such movement while maintaining the pressure-applying means pressed against the shoe. 145
49. In a machine for pressing the bottoms of shoes, a member for applying pressure to the marginal portion of an upper on the bottom of a shoe, said member being movable inwardly over the shoe bottom in response to pressure of the shoe against it, and spring means arranged yieldingly to oppose the inward movement of said member. 150
50. In a machine for pressing the bottoms of shoes, a member for applying pressure to the marginal portion of an upper on the bottom of a shoe, parallel links arranged to move said member inwardly over the shoe bottom in wiping engagement with the upper in response to pressure of the shoe against it, and springs means arranged yieldingly to oppose the inward movement of said member while pressing it against the shoe. 155
51. In a machine of the class described, a wiper for wiping the marginal portion of an upper inwardly over the bottom of a shoe, means for moving said wiper inwardly over the shoe bottom in response to pressure of the shoe against it, and spring means for yieldingly opposing the inward movement of the wiper while pressing it against the upper. 160
52. In a machine for pressing the bottoms of shoes, pressing members arranged to apply pressure to the marginal portion of an upper along the opposite sides of the bottom of a shoe, parallel links arranged to control said members and to move them inwardly over the shoe bottom in response to pressure of the shoe against them, and spring means arranged yieldingly to oppose the inward movement of said members while pressing them against the shoe. 165
53. In a machine for pressing the bottoms of shoes, pressing means movable inwardly over the bottom of a shoe in response to pressure of the shoe thereon, and means for preventing outward return movement of said pressing means until the shoe has been released substantially from the pressure applied. 170
54. In a machine for pressing the bottoms of shoes, pressing means movable inwardly over the bottom of a shoe in response to pressure of the shoe thereon, spring means for yieldingly opposing the inward movement of said pressing means and for thereafter moving it outwardly, and means for preventing the outward movement of the pressing means until the shoe has been released substantially from the pressure applied. 175
55. In a machine of the class described, a wiper for wiping the marginal portion of an upper inwardly over the bottom of a shoe, means for moving said wiper inwardly over the shoe bottom in response to pressure of the shoe thereon, spring means for yieldingly opposing the inward movement of the wiper and for thereafter moving it outwardly, and means for preventing outward return movement of the wiper until the shoe has been released substantially from the pressure of the wiper thereon. 180
56. In a machine for pressing the bottoms of shoes, a member for pressing the marginal portion of an upper on the bottom of a shoe, said 185

- member being movable inwardly over the shoe bottom in response to the pressure of the shoe thereon, and means for imparting to said member outward return movement only after the shoe has been released substantially from the pressure applied.
57. In a machine for pressing the bottoms of shoes, a member for pressing the marginal portion of an upper on the bottom of a shoe, said member being movable inwardly over the shoe bottom in response to pressure of the shoe thereon, spring means for yieldingly opposing the inward movement of the member and for thereafter moving it outwardly, mechanism for preventing the outward return movement of the member, and means to cause said mechanism to release the member only after the shoe has been released substantially from the pressure applied.
58. In a machine for pressing the bottoms of shoes, a member for pressing the marginal portion of an upper on the bottom of a shoe, parallel links arranged to control said member and to move it inwardly over the shoe bottom in wiping engagement with the upper in response to pressure of the shoe against it, spring means for yieldingly opposing the inward movement of the member and for thereafter moving it outwardly, latch mechanism for preventing outward return movement of the member, and means to cause said latch mechanism to release the member after the shoe has been released substantially from the pressure applied.
59. In a machine for pressing the bottoms of shoes, members arranged to engage and press the marginal portion of an upper along the opposite sides of the bottom of a shoe, means for moving said members inwardly over the shoe bottom in wiping engagement with the upper in response to pressure of the shoe against them, spring means for yieldingly opposing the inward movement of said members and for thereafter moving them outwardly, and means for preventing the outward return movement of the members until the shoe has been released substantially from the pressure applied.
60. In a machine for pressing the bottoms of shoes, heated pressing members arranged to engage and press the marginal portion of an upper extending inwardly over an insole along the opposite sides of the forepart and shank portions of the bottom of a shoe and curved to conform substantially to the contour of the shoe bottom, means for moving said members inwardly over the bottom of the shoe in wiping engagement with the upper in response to pressure of the shoe against them, spring means for yieldingly opposing the inward movement of said members and for thereafter moving them outwardly, mechanism for holding the members against outward return movement, and means to cause said mechanism to release the members after the shoe has been released substantially from the pressure applied.
61. In a machine for pressing the bottoms of shoes, pressing means arranged to engage the margin of the upper on a portion of the bottom of a lasted shoe inclined rearwardly from the ball line and shaped in substantial conformity to the desired contour of the shoe in that location, and means for effecting relative movement of said pressing means and the shoe heightwise of the shoe to apply the pressure and for also effecting a relative movement of said pressing means and the shoe lengthwise of the shoe to insure adequate pressure on said rearwardly inclined portion of the shoe bottom.
62. In a machine for pressing the bottoms of shoes, pressing means arranged to engage the margin of the upper on a portion of the bottom of a lasted shoe inclined rearwardly from the ball line and shaped in substantial conformity to the desired contour of the shoe in that location, and means for effecting relative movement of said pressing means and the shoe heightwise of the shoe to apply the pressure and for also forcing the shoe rearwardly to insure adequate pressure on said rearwardly inclined portion of the shoe bottom.
63. In a machine for pressing the bottoms of shoes, pressing means arranged to engage the margin of the upper on a portion of the bottom of a lasted shoe inclined rearwardly from the ball line and shaped in substantial conformity to the desired contour of the shoe in that location, and means arranged to act in response to the application of pressure to the shoe to effect a relative displacement of said pressing means and the shoe lengthwise of the shoe to insure adequate pressure on said rearwardly inclined portion of the shoe bottom.
64. In a machine for pressing the bottoms of shoes, pressing means arranged to engage the margin of the upper on a portion of the bottom of a lasted shoe inclined rearwardly from the ball line and shaped in substantial conformity to the desired contour of the shoe in that location, and a member arranged to act on the inclined top face of the shoe at the rear of the toe to effect a rearward displacement of the shoe as the pressure is applied to insure adequate pressure on said rearwardly inclined portion of the shoe bottom.
65. In a machine for pressing the bottoms of shoes, pressing means constructed and arranged to engage and apply pressure to the margin of the upper on the bottom of a shoe on a last including that portion of the shoe bottom which is inclined rearwardly from the ball line, and means for supporting the last and shoe against the pressure thus applied comprising a member for engaging the top of the heel end of the last and a member for engaging the top of the forepart of the shoe or last, said forepart-engaging member being arranged to act on the inclined top face of the shoe or last at the rear of the toe to effect a rearward displacement of the shoe as the pressure is applied to insure adequate pressure on said rearwardly inclined portion of the shoe bottom.
66. In a machine for pressing the bottoms of shoes, pressing means constructed and arranged to engage and press the marginal portion of an upper extending inwardly over an insole along the opposite sides of the forepart and shank portions of the bottom of a shoe and shaped in substantial conformity to the desired contour of the shoe bottom, and means for effecting a relative displacement of said pressing means and the shoe lengthwise of the shoe in the pressing operation to insure adequate pressure on that portion of the bottom of the shoe which is inclined rearwardly from the ball line.
67. In a machine for pressing the bottoms of shoes, pressing means constructed and arranged to engage and press the marginal portion of an upper extending inwardly over an insole along the opposite sides of the forepart and shank portions of the bottom of a shoe and shaped in substantial conformity to the desired contour of the shoe bottom.

- shoe bottom, and means for supporting the shoe against the pressure thus applied comprising a member arranged to effect a rearward displacement of the shoe to insure adequate pressure on 5 that portion of the bottom of the shoe which is inclined rearwardly from the ball line.
68. In a machine for pressing the bottoms of shoes, pressing members arranged to extend along the opposite sides of the bottom of a shoe, and 10 means for relatively adjusting said pressing members laterally of the shoe comprising mechanism for effecting determinately different amounts of relative adjusting movement of the portions of the members located respectively 15 nearest the opposite ends of the shoe.
69. In a machine for pressing the bottoms of shoes, pressing members arranged to extend along the opposite sides of the bottom of a shoe, and means for relatively adjusting said pressing members laterally of the shoe comprising an adjusting member and devices operated by said member for effecting determinately different amounts of relative adjusting movement of the portions of the pressing members located respectively 20 25 nearest the opposite ends of the shoe.
70. In a machine for pressing the bottoms of shoes, pressing members arranged to extend along the opposite sides of the forepart and shank portions of the bottom of a shoe, and means for 30 relatively adjusting said pressing members laterally of the shoe comprising mechanism for effecting a determinately greater amount of relative adjusting movement of the forepart-pressing portions of said members than of the shank-pressing portions.
71. In a machine for pressing the bottoms of shoes, pressing members arranged to extend along the opposite sides of the forepart and shank portions of the bottom of a shoe, and means for 35 relatively adjusting said pressing members laterally of the shoe comprising an adjusting member and devices operated by said member for effecting respectively relative movements of the forepart-pressing portions and the shank-pressing portions of the pressing members, said devices being so constructed as to effect a determinately greater amount of relative adjusting movement of the forepart-pressing portions than of the shank-pressing portions.
- 50 72. In a machine for pressing the bottoms of shoes, pressing members arranged to extend along the opposite sides of the forepart and shank portions of the bottom of a shoe, and means for 55 relatively adjusting said pressing members laterally of the shoe comprising connected shafts arranged respectively to act on the forepart-pressing portions and the shank pressing portions of the members and having screw threads of different pitch to effect a determinately greater amount of relative adjusting movement of the forepart-pressing portions than of the shank-pressing portions.
- 60 73. In a machine of the class described, wipers arranged to act respectively at the opposite sides of the bottom of a shoe to wipe the marginal portion of the shoe upper inwardly over an insole along the forepart and the shank, and means for 65 relatively adjusting said wipers laterally of the shoe for operating on shoes of different widths comprising mechanism for effecting a determinately greater amount of relative adjusting movement of the forepart-engaging portions than of the shank-engaging portions of the wipers.
74. In a machine of the class described, wipers arranged to act respectively at the opposite sides of the bottom of a shoe to wipe the marginal portion of the shoe upper inwardly over an insole along the forepart and the shank, and means for 70 relatively adjusting said wipers laterally of the shoe for operating on shoes of different widths comprising an adjusting member and devices operated by said members for effecting respectively relative movements of the forepart-engaging portions and the shank-engaging portions of the wipers, said devices being so constructed as to effect a determinately greater amount of relative adjusting movement of the forepart-engaging portions than of the shank-engaging portions.
75. In a machine for pressing the bottoms of shoes, pressing means shaped in substantial conformity to the desired contour of the bottom of a shoe and arranged to support a shoe placed initially thereon bottom downward, and means for determining the proper relation of the shoe to said pressing means comprising members arranged to engage the opposite sides of the shoe at its forepart and other members arranged to engage the opposite sides of its heel end portion.
76. In a machine for pressing the bottoms of shoes, pressing means shaped in substantial conformity to the desired contour of the bottom of a shoe and arranged to support a shoe placed initially thereon bottom downward, and means for determining the proper relation of the shoe to said pressing means comprising different pairs of gage members located at the opposite sides of the forepart and of the heel end of the shoe respectively, the members of each pair being connected for simultaneous adjustment toward or from each other and the forepart-gaging members being also adjustable independently of each other.
77. In a machine for pressing the bottoms of shoes, the combination with bottom-pressing means, of gage members arranged to position the shoe in proper relation to said pressing means by contact with its opposite sides, said members being connected for simultaneous adjustment toward or from each other and being also adjustable each independently of the other.
78. In a machine for operating on the bottoms of shoes of a kind in which the upper is fastened in lasted relation to an insole along the opposite sides of the shoe bottom by cement, wiping and pressing devices arranged to act on the previously lasted marginal portion of the upper of such a shoe along the opposite sides of the shoe between its toe and heel end portions, said devices being constructed and arranged to conform substantially to the curvature of the bottom face of the shoe in the direction of its length, means for heating said devices, and means for moving them inwardly over the shoe bottom in wiping and pressing engagement with the upper while applying heat to the upper and for also effecting relative movement of said devices and the shoe lengthwise of the shoe in the wiping and pressing operation.
79. In a machine for operating on the bottoms of shoes of a kind in which the upper is fastened in lasted relation to an insole along the opposite sides of the shoe bottom by cement, wiping and pressing devices constructed and arranged for substantially continuous engagement with the marginal portion of the upper of such a shoe throughout at least substantially the entire length

- of the shank and ball portions of the bottom of the shoe and shaped to conform substantially to the lengthwise contour of the bottom face of the portions of the shoe which they engage, means for heating said devices, and means for moving them inwardly over the shoe bottom in wiping and pressing engagement with the upper while applying heat to the upper and for also effecting relative movement of said devices and the shoe lengthwise of the shoe in such a direction as to increase the pressure on the upper in locations where the bottom of the shoe is inclined rearwardly from the ball line. 80
80. In a machine for operating on the bottoms of shoes in which the upper is fastened in lasted relation to an insole along the opposite sides of the shoe bottom, wiping and pressing devices arranged to act on the marginal portion of the upper of such a shoe along the opposite sides of the shoe between its toe and heel end portions, said devices being constructed and arranged to conform substantially to the curvature of the bottom face of the shoe in the direction of its length, means for heating said devices, and means for moving them inwardly over the shoe bottom in wiping engagement with the upper and for effecting relative movement of the shoe and said devices heightwise of the shoe to increase their pressure on the upper while applying heat to the upper. 85
81. In a machine for operating on the bottoms of shoes of a kind in which the upper is fastened in lasted relation to an insole along the opposite sides of the shoe bottom by cement, wiping and pressing devices arranged to act on the marginal portion of the upper of such a shoe along the opposite sides of the shoe between its toe and heel end portions, means for heating said devices, and means for moving them inwardly over the shoe bottom in wiping engagement with the upper while progressively increasing their pressure on the upper in a direction heightwise of the shoe and for thereafter maintaining them in pressing relation to the upper while applying heat through the upper to cement between the upper and the insole. 90
82. In a machine for operating on the bottoms of shoes of a kind in which the upper is fastened in lasted relation to an insole along the opposite sides of the shoe bottom by cement, wiping and pressing devices arranged to act on the marginal portion of the upper of such a shoe along the opposite sides of the shoe between its toe and heel end portions, means for heating said devices, and means for moving them inwardly over the shoe bottom in wiping and pressing engagement with the upper and for thereafter increasing their pressure on the upper heightwise of the shoe while applying heat through the upper to cement between the upper and the insole. 95
83. In a machine for operating on the bottoms of shoes of a kind in which the upper is fastened in lasted relation to an insole along the opposite sides of the shoe bottom by cement, wiping and pressing devices arranged to support a shoe placed initially thereon bottom downward and to act on the marginal portion of the upper of the shoe along the opposite sides of the shoe between its toe and heel end portions, means for moving said devices inwardly over the shoe bottom in wiping and pressing engagement with the upper, and electrical heating means movable with said devices to maintain them in a heated condition. 100
84. In a machine for operating on the bottoms of shoes, members movable inwardly over the bottom of a shoe at its opposite sides in pressure-applying relation to the marginal portion of the upper in locations where the bottom of the shoe is inclined rearwardly from the ball line, and means for imparting to said members their inward movements and for also effecting relative bodily movement of said members and the shoe lengthwise of the shoe in such a direction as to increase the pressure of the members on the upper in said locations. 105
